PROCESS AND APPARATUS FOR TREATING HYDROCARBONS

Original Filed Oct. 26, 1923

UNITED STATES PATENT OFFICE

JEAN D. SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR TREATING HYDROCARBONS

Application filed October 26, 1923, Serial No. 670,847. Renewed July 8, 1929.

This invention relates to improvements in treating hydrocarbon oils, and refers more particularly to the production of a light hydrocarbon having the characteristics of gasoline from a heavy hydrocarbon by means of heat and pressure.

In its application, the improvement herein described refers to heating oil under heat and pressure; passing this heated oil to an expansion chamber having a tapered bottom where the heavy residue and carbon precipitated will collect, the residue being mechanically maintained in agitated condition; continuously withdrawing the residue and passing it to settling tanks entirely outside the system, where the carbon will settle and the hot residue returned to the system for further treatment. In addition, I use the distillate, which has already been cracked, to condense the vapors coming from the cracking system.

For years, carbon difficulties have been a serious factor in the cracking of hydrocarbon oils, the length of continuous operation being based on the amount of carbon precipitated in the cracking system. By the above method of allowing the carbon to settle, and withdrawing the hot residue continuously, it will be seen that the clogging up of the expansion chamber will be eliminated, and the system operated for a maximum period of time.

The single figure of the drawing is a diagrammatic side elevational view with parts in section, showing in detail my invention.

Referring in detail to the drawing, 1 designates the charging line provided with the pump 2 and valves 3, 4, and 5. The line 1 may lead to the heating coil 6, which in this instance takes the form of a continuous coil of 3" to 8" pipe, mounted in the furnace 7 which may be heated by the burner 8. The oil after passing through the heating tubes 6 is passed by means of the transfer line 9 provided with a suitable valve, to an expansion chamber 10, which may be completely insulated as shown, and which may have a tapering bottom as shown at 11. A suitable mechanical agitating means 12 such as revolving paddles or fins may be supported

with the tapering portion of the chamber for keeping the contents in constant agitation.

Now referring to one of the features of the invention, I may provide means for continuously withdrawing the residue and precipitated carbon from the bottom of the expansion chamber, through the drawoff line 13 controlled by valve 14. This drawoff line may lead to any one of several settling tanks 15 and 16, of which two are shown in the present instance. In case it may be desired to direct the residue into tank 15, the valve 17 on the connection leading to tank 15 is opened, and the valve 18 on the connection to tank 16 is closed, vice versa. These settling tanks are used merely for the purpose of allowing the residue to precipitate its suspended carbon on the bottom thereof, which carbon may be drawn off through the manholes 19. The tanks may be insulated to prevent the radiation of heat and residue drawoff lines 20 controlled by valves 21 may be provided for continuously withdrawing the hot residue from the settling tanks. It is to be noted that the pressure is reduced by the manipulation of the valves 17 and 18, so that there is substantially no pressure maintained on the settling tanks. The drawoff lines 20 lead to a common line 22 in which is interposed a valve 23, leading to what may be termed the residue rerun pump 24, which pumps the hot residue back to the system for further treatment.

The vapors evolved in the expansion chamber 10 pass through the vapor outlet 25 controlled by suitable valve 26—a to the dephlegmator 26, where the vapors are subjected to dephlegmation, and where a portion of the vapors will condense. The still uncondensed vapors will pass through the vapor line 27 controlled by valve 27—a to the condenser 28 seated in condenser box 29, and thence to receiver 30. This receiver is equipped with the usual pressure relief pipe 31 controlled by valve 32, distillate drawoff line 33 controlled by valve 34, liquid level gauges, pressure gauges, etc.

Referring to another novel feature of my invention, I may return the cracked distillate by means of the pump 35 and feed line 36

and valve 36— α , to the condenser box 29 to be used as a cooling medium for the vapors coming from the dephlegmator. It will be readily seen that a certain percentage of the cracked pressure distillate will vaporize, due to the heat transferred to it from the hot vapors going through the condenser coil 28. I provide a drawoff 37 for withdrawing the revaporized distillate, which may then be condensed and collected in the usual manner.

10 I wish to point out that the product of the revaporation of the cracked distillate will be substantially water-white in color, and will possess all the characteristics of commercial gasoline, ready for use with little further refining. Also, it may be advisable to carry out this latter operation under atmospheric pressure rather than under a pump pressure.

15 The unvaporized portion of the cracked distillate, or pressure distillate bottoms, may be returned, through the line 38 to the charging line as shown. The charging stock may be fed to the heating coils or to the dephlegmator or part of the feed to each, by what may be termed the split feed by manipulation 20 of the valves 3, 4 and 5. The reflux condensate from the dephlegmator 26 will be withdrawn through the line 39 controlled by valve 40, and may be returned to the feed line to the heating coils for further treatment. Interposed in this line 39 is a drawoff 41 controlled by valve 42, connected to the expansion chamber, for allowing the reflux condensate to pass into said expansion chamber.

25 It is understood, of course, that when one settling tank is substantially filled with carbon, it may be cut out by closing the valve on the inlet and diverting the residue into another settling tank by opening its valve.

30 An illustrative run may be as follows: A Mid-Continent gas oil of say 30 to 32° Baumé may be charged into the heating coils 6 and there heated to a temperature of say 750° to 950° F., sufficient to vaporize a very substantial quantity of the oil. The heated oil then passes to the expansion chamber where substantial vaporization takes place, the vapors passing through the dephlegmator and condenser as explained. The whole 35 system may be maintained under a self-generated vapor pressure of 125 pounds more or less, or a differential pressure maintained on different parts of the system if desired. Residuum may be continuously withdrawn from the expansion chamber, the carbon drawn off in the settling tank and the hot residue returned to be retreated.

40 By this method of operation, it is possible to produce 60 to 80% cracked distillate of 48 to 52 Baumé gravity, which on distillation will produce from 35% to 60% commercial Navy specification gasoline.

I claim as my invention:

45 1. A process for cracking oil, consisting in subjecting the oil to conversion conditions of

heat and pressure in a coil, in transferring the heated oil to an enlarged chamber, in dephlegmating the vapors issuing from said chamber, in condensing and collecting the dephlegmated vapors, in continuously discharging unvaporized residual oil from said chamber to a settling zone wherein substantial portions of its free carbon content is precipitated in re-distilling substantial portions of the pressure distillate produced, under a lower pressure than is maintained on the oil in the coil by passage thereof through a zone of heat interchange with uncondensed vapors, in returning regulated quantities of the unvaporized distillate from said zone of heat interchange and carbon-free residual oil from said settling zone to said coil for further treatment.

50 2. An apparatus for treating hydrocarbon oil, comprising a heating coil disposed within a furnace, an enlarged reaction chamber, means connecting said coil with such chamber, a dephlegmator, means for conveying vapors from said enlarged chamber to said dephlegmator, means for introducing oil to said dephlegmator to act as a dephlegmating medium for the vapors therein, a conduit for conveying reflux condensate from said dephlegmator to said enlarged reaction chamber, a valve in said conduit, a second conduit for conveying the reflux condensate directly to the heating coil when said valve is closed, and means for maintaining a self-generated superatmospheric pressure on the oil undergoing conversion in the apparatus.

DISCLAIMER

1,888,051.—*Jean D. Seguy*, Chicago, Ill. PROCESS AND APPARATUS FOR TREATING HYDROCARBONS. Patent dated November 15, 1932. Disclaimer filed September 28, 1933, by the patentee, the assignee, *Universal Oil Products Company*, approving and concurring.

Hereby enters this disclaimer to the subject matter constituting claim 2 of the patent, which reads as follows:

“An apparatus for treating hydrocarbon oil, comprising a heating coil disposed within a furnace, an enlarged reaction chamber, means connecting said coil with such chamber; a dephlegmator, means for conveying vapors from said enlarged chamber to said dephlegmator, means for introducing oil to said dephlegmator to act as a dephlegmating medium for the vapors therein, a conduit for conveying reflux condensate from said dephlegmator to said enlarged reaction chamber, a valve in said conduit, a second conduit for conveying the reflux condensate directly to the heating coil when said valve is closed, and means for maintaining a self-generated super-atmospheric pressure on the oil undergoing conversion in the apparatus.”
